REMOTE CONTROL SYSTEM

Donald S. Bond, Philadelphia, Pa., assignor to
 Radio Corporation of America, a corporation
 of Delaware

Application October 1, 1942, Serial No. 460,339

7 Claims. (Cl. 318—28)

1

This invention relates to remote control systems, and more particularly to an improved system requiring but a single telephone circuit or radio link between the control member and the controlled device.

It is an object of the invention to provide an improved method of and means for transmitting the signals required to establish control of the position of a movable object in response to the position of a control member.

Another object is to provide an improved method of and means for deriving a control signal including a modulated carrier, in which the phase relationship between certain components of the signal corresponds to the intelligence to be transmitted.

A further object is to provide an improved method of and means for converting a signal comprising two voltages of equal frequency and varying phase relationship into a signal which may be transmitted through a single channel, and reconverting said signal after transmission.

These and other objects will become apparent to those skilled in the art upon consideration of the following description of the invention, with reference to the accompanying drawing, of which Fig. 1 is a schematic block diagram of an embodiment of the invention, Fig. 2 is a circuit diagram of a balanced modulator, Fig. 3 is a circuit diagram of a bridge type mixer, and Fig. 4 is a circuit diagram of a phase discriminator.

Referring to Fig. 1, a control device, of which the angular position is to be reproduced at a remote point, is mechanically connected to a phase shifter 3. An oscillator 5, operating at a frequency of, for example, 60 cycles per second, is connected to the input of the phase shifter 3. The device 3 is constructed like a goniometer or in any suitable manner so that it provides a continuous change of phase upon rotation of its control shaft. The output of the phase shifter is applied to a balanced modulator 7. A second oscillator 9 operating at a frequency of, for example, 1000 cycles per second is also connected to the balanced modulator. The output of the balanced modulator 7 is applied to a mixer circuit 11, which is also connected to the oscillator 5.

The output of the mixer 11 is transmitted over a telephone circuit or radio link to the receiver station, where the motion of the device 1 is to be duplicated by a load device 39. The transmitted signal is applied to filters 13 and 15. The filter 13 is connected to a demodulator 17 which is connected in turn through an amplifier 19 to a phase shifter 21 similar in construction to the

2

phase shifter 3. The output of the phase shifter 21 is applied to a phase detector 23. The output of the filter 15 is applied through an amplifier 25 to the phase detector 23. The output of the detector 23 is connected through a low pass filter 27 to a balanced modulator 29. Voltage from an alternating current power line 31 is applied to the modulator 29 through a phase adjuster 33. The output of the modulator 29 is connected to an amplifier 35. A two phase motor 37 is provided with one phase connected to the output of the amplifier 35 and the other phase connected to the power line 31. The motor 37 is mechanically connected to the phase shifter 21 and to the load device 39.

The operation of the system is as follows: The output of the oscillator 5 is shifted in phase by the device 3 to an extent depending on the position of the control member 1. The 60 cycle output of the phase shifter 3 is combined in the balanced modulator 7 with the 1000 cycle output of the oscillator 9. The 60 cycle component is suppressed by the action of the balanced modulator, thus providing an output comprising the 1000 cycle sidebands of a 60 cycle carrier, namely, 940 cycles and 1060 cycles, as well as the 1000 cycle modulation. The phase of the sideband frequencies with respect to a fixed reference is similar to that of the output of the phase shifter 3 with respect to that of the oscillator 5. Phase reference voltage is provided by the oscillator 5, and is added to the products of the modulator 7 in the mixer circuit 11. The function of the mixer 11 is merely that of superposition, not modulation. The mixer 11 is arranged to isolate the oscillator 5 from the modulator 7 to prevent interaction between their outputs, as more fully described hereinafter. The output of the mixer 11 thus comprises components at 940 cycles, 1000 cycles, 1060 cycles, and a fixed-phase component at 60 cycles.

The higher frequency components are separated at the receiver station by the filter 13. The demodulator 17 regards these components as a 1000 cycle carrier with 60 cycle sidebands at 940 and 1060 cycles, and accordingly provides a 60 cycle output. This 60 cycle output varies in phase with the variations in phase of the output of the phase shifter 3 at the transmitter.

The 60 cycle constant phase component of the transmitted signal is separated by the filter 15, amplified by the amplifier 25, and applied to the phase detector 23. The variable phase 60 cycle output of the demodulator 17 is amplified by the amplifier 19 and applied through the phase shift-

er 21 to the phase detector 23. The output of the phase detector 23 is a D.-C. voltage, having a magnitude related to the magnitude of the phase displacement between the output of the phase shifter and the reference phase voltage, and a polarity depending upon the direction of said displacement. This voltage is conducted through the filter 27 to remove any remaining ripple from the 60 cycle inputs, and controls the balanced modulator 29, varying the magnitude and polarity of the voltage derived from the power line 31 through the phase adjustor 33. It should be noted that the power line frequency may be entirely independent of the frequency of the local oscillator 5. In any event the power line frequency output of the balanced modulator 29 is amplified by the amplifier 35 and used to energize the winding 41 of the motor 37. The motor winding 43 is energized directly from the power line. The phase adjustor 33 is adjusted to provide quadrature phase relationship between the voltages applied to the two motor windings. The motor 37 runs in the proper direction to drive the phase shifter 21 toward a position such that its output is 90° out of phase with the reference phase voltage. At this point the output of the phase detector becomes zero, the power line frequency output of the modulator 29 likewise drops to zero, and the motor winding 42 is de-energized, stopping the motor. Upon further displacement of the control device 1, the same action occurs and the phase shifter 21 is again rotated to stop the motor. Consequently, the controlled device 39, being mechanically connected to the phase shifter 21 and the motor 37, is maintained in positional agreement with the control device 1.

Fig. 2 shows a circuit which may be used for the balanced modulators 7 and 29. A pair of tubes 41 and 43 are connected in push-pull to a load circuit such as the primary 45 of an output transformer. A pair of input terminals 47 and 49 is connected to the grids of the tubes 41 and 43, and two resistors 51 and 53 are connected in series between the two grids. A second pair of input terminals 55 and 57 is connected between the junction of the resistors 51 and 53 and the common grid return circuit of the tubes 41 and 43.

When no input is applied to the terminals 47 and 49, no voltage appears in the output circuit, regardless of the input to the terminals 55 and 57, because the individual outputs of the two tubes are applied to the load in phase opposition. However if a voltage is applied to the terminals 47 and 49, it is amplified and applied to the load, and at the same time modulates any input to the terminals 55 and 57. This action occurs because the circuit is periodically unbalanced, first in one direction and then in the other by the input to the terminals 47 and 49. In the circuit of Fig. 1, the output of the oscillator 9 is connected to the terminals 47 and 49 of the modulator 7, and the output of the phase shifter 3 is connected to the terminals 55 and 57. The modulator 29 has its terminals 55 and 57 connected to the phase adjustor 33 and the terminals 47 and 49 to the filter 27.

Fig. 3 shows a suitable circuit for the mixer 11. The center tapped secondary 61 of a transformer 59 is connected to the primaries 63 and 65 of a pair of transformers 61 and 68 to form a balanced bridge circuit. A network 62 is connected to the transformer 68 to balance the impedance of the load on the transformer 67. A voltage applied to the primary of the trans-

former 59 produces no output at the terminals 69 and 71, and a voltage applied to these terminals produces no effect at the primary of the transformer 59. The voltage across the primary 65 of the transformer 67 is proportional to the sum of the two input voltages. This circuit or some equivalent thereof is necessary in the system of Fig. 1 to prevent plate circuit modulation in the modulator 7 by voltage from the oscillator 5.

Fig. 4 shows the circuit of the phase detector 23 of Fig. 1. Two diodes 73 and 75 are connected as shown between center tapped input and output circuits 77 and 79. The variable phase signal voltage is applied to the diodes in push pull through a transformer 81, and the constant phase reference voltage is applied to the two diodes in phase between the center taps of the input and output circuits. When the two inputs are in phase at one diode, they are out of phase at the other, thus causing current to flow through the corresponding section of the output circuit, toward the center tap. When the two inputs are in quadrature, no output voltage is produced. Thus the device provides a unidirectional output voltage, of magnitude and polarity depending on the phase relationship between the two input voltages.

It is usually necessary, in a control system of the follow-up type, in which the driving motor operates to reduce the control signal to zero value, to incorporate some means to prevent hunting. Although such anti-hunting system has been omitted from the above description for the sake of clarity, one suitable system is described in U. S. Patent No. 2,208,623 to D. S. Bond.

Thus the invention has been described as an improved remote control system. A low frequency voltage is generated and shifted in phase to correspond to the control information to be transmitted. The shifted voltage is then modulated, the shifted low frequency carrier is suppressed, and replaced by the original constant phase low frequency voltage. This signal is transmitted to the control station, when the constant phase voltage is separated from the variable phase modulation. The modulation is detected, providing variable phase low frequency voltage. This voltage is compared with the constant phase low frequency component of the signal, providing a control voltage which is used to control an electric motor. A single signal channel suffices to carry all of the necessary information, and in fact may be used simultaneously for a plurality of systems of the type described, operating with different modulation frequencies.

I claim as my invention:

1. The method of transmitting control information including the steps of generating an alternating voltage, shifting the phase of said voltage in response to the information to be transmitted, generating a second alternating voltage of substantially higher frequency than said first alternating voltage, modulating said phase shifted voltage in opposite phases by said second alternating voltage to provide two modulated signals whose carriers are 180 degrees out of phase with each other and whose respective side bands are in phase with each other, combining said modulated signals to cancel said carriers and provide a suppressed carrier signal comprising only said side band signals, adding to said suppressed carrier signal a constant phase alternating voltage of the same frequency as said phase shifted voltage, transmitting the resultant combined signal,

receiving said transmitted signal, separating the constant phase component of said signal from the variable phase sideband components thereof, demodulating said variable phase components to provide a variable phase alternating voltage, combining said variable phase voltage with said constant phase signal component to produce a direct current related in magnitude and polarity to the difference in phase of said variable phase voltage and said constant phase signal component, shifting the phase of said variable phase component in response to said direct current so as to reduce said phase difference to zero, and deriving control information in response to the extent of said phase shift of said variable phase component.

2. The method of transmitting a variable phase control voltage and a constant phase reference voltage through a single channel including the steps of generating a modulating voltage of substantially different frequency from said first-mentioned voltages, modulating one of said first-mentioned voltages in opposite phases by said modulating voltage to provide two modulated signals whose carriers are in phase opposition to each other and whose corresponding side bands are in phase with each other, combining said modulated signals to cancel said carriers and provide a suppressed carrier signal comprising only said side-band signals, adding the other of said two first-mentioned voltages to said suppressed carrier signal, to provide a combined signal transmitting said combined signal, receiving said combined signal, separating said suppressed carrier signal component from said added voltage component, demodulating said suppressed carrier signal component to produce a voltage similar to the carrier component which was suppressed, combining said last mentioned voltage with said added voltage component, and deriving a control signal from the product of said combination.

3. A control system including a source of relatively low frequency alternating current, a control member arranged to shift the phase of said alternating current, a source of relatively higher frequency alternating current, a balanced modulator arranged to modulate said lower frequency current with said higher frequency current, a mixer connected to combine the output of said balanced modulator with that of said source of low frequency current, means for transmitting and means for receiving the combined signal output of said mixer, filter means arranged to separate the low frequency component from the higher frequency components of said combined signal, a demodulator arranged to derive from said higher frequency components a variable phase low frequency voltage, a phase detector connected to respond to said variable phase voltage and said low frequency signal component, means responsive to the output of said phase detector to shift the phase of said variable phase component so as to produce zero output from said phase detector, and means for operating a controlled member as a function of said phase shift.

4. A system for reproducing at a remote point the phase relationship between a variable phase control voltage and a constant phase reference voltage, including an auxiliary source of alternating current, balanced modulator means for modulating one of said voltages with the output of said auxiliary source, a mixer arranged to combine the other of said voltages with the output of said modulating means, means for trans-

mitting and receiving through a single channel the combined output signal of said mixer, filter means for separating the modulated component of said signal from the remainder thereof, and demodulator means arranged to derive from said component a modulation voltage corresponding to one of said original voltages.

5. A remote control system including means for deriving a variable phase control signal and 10 a constant phase reference signal, an auxiliary source of alternating current, a balanced modulator arranged to modulate one of said signals with the output of said auxiliary source, means for transmitting and receiving the output of said balanced modulator and said other signal, a demodulator arranged to derive from said modulator output a voltage similar to the signal input to said modulator, and motor control means responsive to the phase relationship between said voltage and said unmodulated signal.

6. A control system including a source of A.-C. voltage, means connected to said source for deriving, in response to control information to be transmitted, a second A.-C. voltage variable in phase with respect to said first A.-C. voltage; a second source of A.-C. voltage of different frequency from said first and second A.-C. voltages, a balanced modulator, means for applying said variable phase A.-C. voltage and said voltage from said second source to said balanced modulator to provide a signal comprising a carrier of the frequency of said second source and sidebands corresponding to said variable phase A.-C. voltage, means for combining said signal with said first A.-C. voltage to provide a composite signal; means responsive to said composite signal to produce voltages having the same phase relationship to each other as said first and second A.-C. voltages, said last mentioned means comprising 35 a filter connected to separate said first A.-C. voltage from said composite signal, and a demodulator connected to said filter to derive from the remainder of said composite signal an A.-C. voltage corresponding to said second A.-C. voltage.

7. In a remote control system in which control information is derived in the form of two A.-C. voltages of the same frequency but of variable phase with respect to each other, a system for 50 transmitting said information over a single channel including a source of carrier voltage, balanced modulator means for modulating said carrier voltage with one of said A.-C. voltages to provide a suppressed carrier signal including sidebands corresponding to said modulating voltage, means 55 for combining said suppressed carrier signal with the other of said A.-C. voltages to provide a composite signal, and means including a demodulator for deriving from said composite signal two A.-C. voltages having the same phase relationship to each other as said first mentioned two A.-C. voltages.
